(57) **CLAIM**

The ornamental design for an electronic device with graphical user interface as shown and described.

DESCRIPTION

FIG. 1 is a top front isometric view of an electronic device with graphical user interface showing the claimed design; FIG. 2 is a top rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a front isometric view thereof showing the claimed design in an environment in which it may be used.

The broken lines in the figures show portions of the electronic device or environment that form no part of the claimed design.
